UNITED STATES PATENT OFFICE

151,784

DESIGN FOR A TRAFFIC SIGNAL OBSERVATION LENS

Howard C. Riemann, West Allis, Wis., assignor
to The Fulton Company, Milwaukee, Wis., a
corporation of Wisconsin

Application September 8, 1947, Serial No. 141,250

Term of patent 14 years

(Cl. D14—6)

To all whom it may concern:

Be it known that I, Howard C. Riemann, a citizen of the United States, residing at West Allis, in the county of Milwaukee and State of Wisconsin, have invented a new, original, and ornamental Design for Traffic Signal Observation Lens, of which the following is a description, reference being had to the accompanying drawing, forming a part thereof.

In the drawing:

Fig. 1 is a top or plan view of a traffic signal observation lens, embodying my new design;

Fig. 2 is a side view of the traffic signal observation lens of Fig. 1;

Fig. 3 is a view of the lens looking toward the lower end of Fig. 1; and

Fig. 4 is a view of the lens looking toward the upper end of Fig. 1.

I claim:

The ornamental design for a traffic signal observation lens, substantially as shown.

HOWARD C. RIEMANN.
